UNITED STATES PATENT OFFICE.

REGINALD B. MILDON, OF LANSDOWNE, PENNSYLVANIA, ASSIGNOR TO WESTINGHOUSE ELECTRIC AND MANUFACTURING COMPANY, A CORPORATION OF PENNSYLVANIA.

STOKER.

Application filed October 27, 1920. Serial No. 420,015.

To all whom it may concern:

Be it known that I, REGINALD B. MILDON, a citizen of the United States, and a resident of 20 W. Baltimore Ave., Lansdowne, in the county of Delaware and State of Pennsylvania, have invented a new and useful Improvement in Stokers, of which the following is a specification.

My invention relates to mechanical stokers, particularly of the underfeed type, and it has for its object to provide apparatus of the character designated which shall be effective in producing uniform fuel distribution throughout a fire box and which shall further be of relatively small overall height, thus adapting the structure for installation in fire boxes having low boiler settings, as, for example, those designed for hand firing.

A further object of my invention is to provide a compact underfeed stoker structure which may be readily applied to and withdrawn from a furnace.

In the accompanying drawings, Fig. 1 is a vertical sectional view of the stoker mechanism embodying my invention; Fig. 2 is a view, partially in section and partially in elevation of the structure shown in Fig. 1, being taken on the plane II-II thereof; and Fig. 3 is a plan view of the apparatus shown in Fig. 1.

In the production of mechanical stokers, it has been proposed to supply the fuel to a main retort, forcing it therethrough by fuel pushers and to then pass the fuel on to branch retorts opening directly from the main retort, auxiliary pushing means also being employed in the branch retorts in order to keep the fuel mass in motion.

With this construction, difficulties may be encountered in causing a smooth and undisturbed passage of the fuel from the main to the branch retorts, together with other difficulties to be hereinafter more fully set forth.

In accordance with my invention, I propose to provide a main retort having smooth and unbroken side walls throughout its length, and I supply fuel thereto in the usual manner by a fuel pusher or ram so designed as to raise the fuel at the same time that it is forced longitudinally of the main retort.

Auxiliary retorts are disposed beyond the barriers or side walls of the main retort and these auxiliary retorts are further prefer-

ably provided with fuel-moving means so arranged as to maintain motion of the fuel bed away from the main retort.

By this construction, a uniform and continuous flow of the fuel to all portions of the fuel bed, together with efficient combustion thereof is maintained.

The entire structure thus set forth is preferably mounted on wheels for ready insertion into and withdrawal from a furnace, although, obviously, the stoker structure operates with equal effectiveness if permanently mounted.

Referring to the drawing for a more detailed understanding of my invention, I show a main retort at 5 in Figs. 1 and 3, formed by side walls or barriers 6-6 and a bottom plate 7. This main retort extends inwardly from a fuel hopper 8, shown in dotted lines in Fig. 1 and in full lines in Fig. 3, and fuel is moved from the hopper 8 into the retort 5 by a ram 9 having a somewhat sharply inclined rear face so as to exert a lifting action on the fuel at the same time that it is forced backwardly.

One or more auxiliary rams 10 are mounted in the bottom of the retort 5 to slide upon the bottom plate 7, these auxiliary rams being provided with driving lugs 11 projecting through slots in the plate 7 and being connected to an operating rod 12 for actuating of the auxiliary rams. Certain of the working faces of these auxiliary rams are so inclined so as to exert a lifting action upon the fuel.

The side walls 6 are preferably formed by a series of tuyère sections 13, as clearly shown in Fig. 2, and the tuyère openings 13' in these tuyère sections are in communication with an air chamber or wind box 14 formed below the stoker, as is usual practice.

Auxiliary retorts 20-20 are formed on each side of the main retort 5, each of these retorts comprising side tuyère boxes 21-21 and a bottom portion made up of a fuel plate 22 and a ram member 23 mounted to reciprocate thereupon. The auxiliary retorts 20-20 discharge upon ash plates 24-24 of any desired form. The auxiliary retorts 20-20 and the tuyère boxes 21-21 are arranged alternately the width of the furnace, and are terminated at their inner ends by the tuyère sections 13-13, the latter constituting the continuous side walls 6-6 of the

main retort 5. The retorts 20—20, the tuyère boxes 21—21 and the sections 13—13 are each preferably made uniform in size so as to be interchangeable and hence readily 5 replaceable.

The tuyère boxes 21—21 are provided with tuyère plates 21^a having air delivery openings 21^b, the upper faces of the tuyère plates forming a gradual slope from the 10 upper surface of the barrier 6 to a point adjacent the ash plates. In a like manner the bottoms of the auxiliary retorts are shown as provided with a gentle slope away from the main retort, although, by providing 15 sufficient fuel-actuating means, the bottoms of the auxiliary retorts may be level, or even have a slight upward slope away from the main retort. The pusher members 23 are provided with two or more fuel-engaging 20 members 25—25 and are furthermore designed to be actuated by a variable throw linkage mechanism 26, 27 connected to a rod 28, coupled in turn to the stoker driving means which also drives the connecting 25 rod 12 to the variable stroke fuel pushers 10 in the main retort 5. The outer surfaces or backs of the tuyère sections 13 at the inner ends of the auxiliary retorts 20—20 are given a smooth and gradual slope, as shown 30 at 29, this slope merging into the bottoms of the auxiliary retorts 20—20.

The entire stoker structure thus set forth is shown as mounted on wheels 30—30 running on tracks 31—31 so that the entire 35 structure may be readily withdrawn for inspection or repair, this feature being of particular importance in connection with the low boiler settings with which my stoker is adapted to be employed, the space 40 over the stoker frequently being too small for ready inspection and repair in situ. Particular attention is directed to this feature as the complete stoker with its small overall height, its light yet rugged construction, its effective fuel distribution and 45 its ready removability adapt it for use in many installations where the installation of mechanical stokers has hitherto been deemed unfeasible.

50 Having thus described the arrangement of a stoker mechanism embodying my invention, the operation thereof is as follows: Upon starting the driving mechanism, the main ram 9 and the auxiliary rams 23—23 55 are reciprocated through strokes determined by the quality of fuel and the desired rate of combustion. Coal introduced into the hopper 8 passes into the main retort 5 and combustion is initiated by means 60 of air flowing from the tuyère sections 13. As the fuel mass is moved backward, it is also raised by the rams 9 and 10 and lifted over the side walls or barriers 6—6, falling 65 into the upper ends of the auxiliary retorts where its travel is kept up by means of the

auxiliary rams 23—23. It should be noted that the fuel travel thus set forth is relatively smooth and free from obstruction, there being no corners or other fixed members in the path of the fuel such as would 70 tend to cause jamming and clogging thereof. The smooth and unbroken side walls 6—6 permit the ready passage of fuel therealong and thereover and combustion is greatly aided by the copious supply of air 75 which may be supplied through these side walls, this copious air supply further aiding in that it maintains the side walls at relatively low temperatures and, therefore, retards the destruction thereof. 80

The fuel overflowing from the main retort slides down the smooth outer surfaces of the sections 13 into the auxiliary retorts in such manner that there is a uniform and continuous supply of fuel thereto as is demanded by efficient combustion. In passing over the sections 13, there is a tendency to break up the caked mass if the coking is of such a nature as to lead to caking and this factor leads to still more efficient combustion. 85

90 It should be particularly noted that by reason of the structure set forth, gravity is relied upon but little, if at all, for the forward motion of the fuel, the extensive use of fuel pushers insuring uniform fuel supply in all parts of the fire box. Thus the pitch given to the bottoms of the auxiliary retorts may be very slight and it results that the vertical thickness of the entire stoker structure is relatively small, thus permitting the stoker to be installed in many fire boxes designed for hand firing and which are not adapted for many types of underfeed stokers because of inadequate 100 height. 105

Furthermore, the specific structure shown prevents the formation of a high fuel crown and this factor also permits the installation of this apparatus in fire boxes 110 of relatively low head room.

While I have shown my invention in but one form, it will be obvious to those skilled in the art that it is not so limited but is susceptible of various other changes and 115 modifications, without departing from the spirit thereof and I desire, therefore, that only such limitations shall be placed thereupon as are imposed by the prior art or as are specifically set forth in 120 the appended claims.

I claim:

1. In an underfeed stoker structure, the combination with a main retort having continuous side walls, of auxiliary retorts disposed beyond said side walls and arranged to receive fuel from said main retort. 125
2. In an underfeed stoker structure, the combination with a main retort having continuous side walls and provided with fuel- 130

- feeding means, of a plurality of auxiliary retorts separated from said main retort by said side walls and arranged to receive fuel from said main retort. 65
- 5 3. In an underfeed stoker structure, the combination with a main retort having continuous side walls and provided with fuel-feeding means, of a plurality of auxiliary retorts separated from said main retort by 70
- 10 said side walls and arranged to receive fuel from said main retort, each of said auxiliary retorts being provided with fuel-moving means.
4. In an underfeed stoker structure, the 15 combination with a main retort having continuous side walls, provided with air inlet openings throughout substantially the entire length thereof, of auxiliary retorts disposed beyond said side walls and arranged to receive fuel from said main retort. 20
5. In an underfeed stoker structure, the combination with a main retort having continuous side walls provided with air inlet openings throughout substantially the entire 25 length thereof and provided with fuel-feeding means, of a plurality of auxiliary retorts separated from said main retort by said side walls and arranged to receive fuel from said main retort. 30
- 30 6. In an underfeed stoker structure, the combination with a main retort having continuous side walls provided with air inlet openings throughout substantially the entire length thereof and fuel-feeding means for 35 said main retort, of a plurality of auxiliary retorts separated from said main retort by said side walls and arranged to receive fuel from said main retort, each of said auxiliary retorts being provided with fuel-moving means. 40
- 40 7. In an underfeed stoker structure, the combination with a primary retort for the initial coking and combustion of fuel, of a secondary retort arranged to receive fuel 45 from the primary retort for completing said combustion, said retorts being separated by a barrier over which the fuel is forced to pass, said secondary retort having its axis at substantially a right angle to the axis of the main retort. 50
- 50 8. In an underfeed stoker structure, the combination with a primary retort for the initial coking and combustion of fuel, of a secondary retort arranged to receive fuel 55 from the primary retort for completing said combustion, said retorts being separated by a barrier over which the fuel is forced to pass, and said barrier being provided with air-admitting openings, the direction of fuel 60 travel in the secondary retort being substantially at a right angle to the direction of main fuel travel in the primary retort.
9. An underfeed stoker comprising a main fuel-feeding device, a main retort to receive the fuel having tuyère sections forming 65 continuous side walls therefor, auxiliary retorts arranged at the side of the main retort to receive fuel therefrom, and means for lifting the fuel out of the main retort and distributing it to the auxiliary retorts. 70
10. An underfeed stoker comprising a main fuel-feeding mechanism, a main retort to receive the fuel having tuyère sections forming continuous side walls therefor, auxiliary retorts at the side of the main retort 75 and arranged to receive fuel therefrom, fuel pushers in the main and auxiliary retorts, and adjustable means associated with the fuel pushers for regulating the distribution of fuel in the main and auxiliary retorts. 80
11. An underfeed stoker comprising a main fuel-feeding mechanism, a main retort to receive the fuel, auxiliary retorts arranged at the side of the main retort to receive fuel therefrom, the main retort including tuyère members forming a continuous side wall for the main retort and inner 85 walls for the auxiliary retorts. 85
12. An underfeed stoker comprising a main retort having continuous side walls, means for feeding fuel into the main retort, means for causing a forward and lifting movement of the fuel in the main retort, a grate section disposed contiguous to one of said side walls and adapted to receive fuel 90 from the main retort, said grate section comprising alternate auxiliary retorts and tuyère sections. 95
13. In an underfeed stoker, the combination with a main retort having continuous side walls, of a furnace floor adapted to receive fuel overflowing from the main retort, said floor comprising alternately disposed auxiliary retorts and tuyère sections. 100
14. In an underfeed stoker, the combination with a main retort having continuous side walls, of a furnace floor adapted to receive fuel overflowing from the main retort, said floor comprising alternately disposed auxiliary retorts and tuyère section, fuel feeding means associated with said main retort and fuel feeding means associated with the several auxiliary retorts. 105
15. In an underfeed stoker, the combination with a main retort having continuous side walls, of a furnace floor adapted to receive fuel overflowing from the main retort, said furnace floor comprising a plurality of air delivery tuyère sections extending transversely from the main retort, and imperforate fuel supporting sections disposed between adjacent tuyère sections. 115
- In testimony whereof, I have hereunto 120 subscribed my name this 22nd day of October, 1920.

REGINALD B. MILDON.
